Assistant Examiner — Andrea Marie McKay

(57) **CLAIM**

The ornamental design for a sink faucet splash guard, as shown and described.

DESCRIPTION

FIG. 1 is a perspective view of an embodiment of a sink faucet splash guard in accordance with the new design; FIG. 2 is a top view of the sink faucet splash guard shown in FIG. 1;

FIG. 3 is a bottom view of the sink faucet splash guard shown in FIG. 1;

FIG. 4 is a rear view of the sink faucet splash guard shown in FIG. 1;

FIG. 5 is a front view of the sink faucet splash guard shown in FIG. 1;

FIG. 6 is a left side view of the sink faucet splash guard shown in FIG. 1;

FIG. 7 is a right side view of the sink faucet splash guard shown in FIG. 1;

FIG. 8 is a perspective view of another embodiment of a sink faucet splash guard in accordance with the new design;

FIG. 9 is a top view of the sink faucet splash guard shown in FIG. 8;

FIG. 10 is a bottom view of the sink faucet splash guard shown in FIG. 8;

FIG. 11 is a rear view of the sink faucet splash guard shown in FIG. 8;

FIG. 12 is a front view of the sink faucet splash guard shown in FIG. 8;

FIG. 13 is a left side view of the sink faucet splash guard shown in FIG. 8; and,

FIG. 14 is a right side view of the sink faucet splash guard shown in FIG. 8.

There are symbolic break lines along the length of the sink faucet splash guard. The break lines and the areas between the break lines form no part of the claimed design.

The broken lines depict portions of the sink faucet splash guard that form no part of the claim.

1 Claim, 8 Drawing Sheets
